FIG. 5.

INVENTOR
Matthew Krompigel
BY John H. Honey
ATTORNEY.

UNITED STATES PATENT OFFICE.

MATHEW KROMPIGEL, OF YOUNGSTOWN, OHIO.

GARMENT-SUPPORTER.

1,383,642.

Specification of Letters Patent. Patented July 5, 1921.

Application filed August 27, 1919. Serial No. 320,126.

To all whom it may concern:

Be it known that I, MATHEW KROMPIGEL, a citizen of the United States, residing at Youngstown, in the county of Mahoning 5 and State of Ohio, have invented a new and useful Improvement in Garment-Supporters, of which improvement the following is a specification.

My invention relates to improvements in 10 devices for supporting garments; the object of my invention is to produce a device of this character capable of supporting garments or wearing apparel, a hat and an umbrella. I accomplish this by means of the 15 device hereinafter more specifically described, reference being had to the accompanying drawings forming part hereof, in which,

Figure 1 is a plan view.

Fig. 2 is a front elevation.

Fig. 3 is a central section on line 3—3 of Fig. 2.

Fig. 4 is an enlarged elevation of the trouser support.

Fig. 5 is a central section on line 5—5.

Fig. 6 is a side view of Fig. 4.

Referring to said drawings, 1 is a suspending line formed of twisted wire, a portion 2 thereof supporting a frame 3 which 30 is circular, elliptical or other configuration, having outwardly projecting flanges *a*, and a projecting prong *b*, to which a hat may be suspended, the flanges furnishing a support for the rim thereof. The said suspending member extending to the lower edge of said frame and terminates in a bifurcated portion 4, in the hook ends of which a bearing is formed for the reception of a short shaft or rod 5, the said rod being adapted 40 to receive the hook ends of the bifurcated portion 6, of the coat suspending member, the said coat suspending member terminating in a bifurcated portion 7, which is connected to the coat supporter 8. Between the 45 said bifurcated portion 7 hook members 9 of the trouser supporter are suspended. The

said trouser supporters comprise in addition to said members 9 the downwardly projecting members 10 which consist of vertically disposed arms 11 which terminate in laterally projecting horizontally disposed grasping members *c*. The latter members are corrugated or convoluted preferably for the purpose of more tightly holding the trousers inserted or grasped therebetween. 50 The said grasping members *c* are held in closed position by the springs 12. The upper outer ends of the said grasping members may be opened or separated. Prongs 16, 16, project forwardly and rearwardly 60 from the main support and are adapted to receive or carry umbrellas. A mirror may be inserted in the opening of the frame, 3, from which projects the prong, *b*, adapted to support a hat. An outwardly projecting 65 member, 17, secured to the top or upper end of the device, is adapted to receive a cover, which is adapted to inclose the entire structure, for the purpose of preventing the admission of dust thereto, said outwardly projecting member, 17, serving to hold said cover in distended form.

Having described my invention what I claim and desire to secure by Letters Patent, is:—

A garment supporter comprising a vertically twisted wire suspending line, a rectangular frame supported upon the top of said line, a depending wire member connected to said line, supporting fingers projecting from said wire member, a circular sheet metal frame in engagement with said fingers, and hangers suspended from the said depending wire member.

In testimony whereof, I have hereunto signed my name in the presence of two subscribing witnesses.

MATHEW KROMPIGEL.

In the presence of—

JOHN SHRINA,
MICHAEL FERRANDO.
